UNITED STATES PATENT OFFICE

RALPH K. MERRILL, OF GRAND RAPIDS, MICHIGAN, ASSIGNOR TO AMERICAN SEATING COMPANY, OF GRAND RAPIDS, MICHIGAN, A CORPORATION OF NEW JERSEY

HINGE FOR MOUNTING DESK TOP LIDS

Application filed August 9, 1930. Serial No. 474,237.

The present invention relates to hinges for mounting the lids of desk tops and the like; and its object is to provide such a mounting hinge which may be securely and rigidly fastened to said parts; and further, to provide in such a hinge improved means for preventing the warping of the lid; and further, to provide in such a hinge improved means for mounting the same in adjustable relation to the lid.

These and any other and more specific objects hereinafter appearing are attained by, and the invention finds preferable embodiment in, the device particularly described in the body of this specification and illustrated by the accompanying drawing forming a part hereof, in which:—

Figure 1 is a bottom plan view of a swingable lid and a portion of a desk top on which the lid is mounted;

Figure 2 is a vertical sectional view thereof taken on line 2—2 of Figure 1;

Figure 3 is a vertical sectional view of certain parts of the same taken on line 3—3 of Figure 1; and

Figure 4 is a vertical sectional view of certain parts taken on line 4—4 of Figure 1.

In the drawing, a desk structure is shown having a box top forming an upwardly open chamber 1 and a fixed horizontal wall 2 closing the rear portion of the chamber. On this wall 2 is mounted a swingable lid 3 adapted to be raised and lowered to open and to completely close the chamber. This lid is mounted on said wall 2 by a hinge having two leaves 4, 5, connected by a pintle 6, the leaf 4 being secured to wall 2 as by screws 7.

The lid 3 has a groove 8 in its under side, extending in its transverse direction and having overhanging sides 9, 9 which, as particularly shown in Figure 3, are inclined, and diverge inwardly or toward the bottom 10 of the groove. The hinge's leaf designated generally 5 is elongated in the direction of the groove and is thrust endwise thereinto.

This elongated leaf has a middle or web portion 11 and springable flange portions or sides 12, 12 which extend laterally inwardly from said middle portion, divergingly from

each other and parallelly with the inclined sides 9, 9 of the groove. To seat this elongated leaf 5 in tight contact with said sides of the groove, a filler strip 13 having inclined edges 14 is driven into the groove between 55 and in contact with the bottom 10 of the groove and the inclined sides 12, 12 of said leaf, so as to bind or clamp said sides of the elongated leaf between the filler strip and the inclined sides 9, 9 of the groove. It 60 will be seen that the said elongated leaf is thus not only rigidly secured to the lid 3, but that it also prevents the same from warping and like deformation.

This elongated leaf 5 has an outer end portion 15 which extends outside the groove and contacts the under surface of the lid and has a longitudinally extending slot 16 through which a screw 17 is passed into the lid, the lid being thus adjustable forwardly- 70 rearwardly on said leaf. In the chamber 1 of the desk top a friction plate 18 is mounted, on which frictionally bears (in the opening and closing movement of the lid) a friction plate 19 formed integrally with the 75 hinge's elongated leaf 5 by bending over a portion thereof.

As indicated in the drawing, the leaf designated generally 5 is desirably formed of two metal plates, one of them, 20, having the 80 bearings for the pintle 6 and the other, 21, being the part seated in the groove, these plates 20, 21 being united by rivet portions 22 and spot welding indicated at 23. The lid 3 is thus mounted on the desk top by a 85 pair of these hinges adjacent the ends respectively of the structure.

The invention being intended to be pointed out in the claims, is not to be limited to or by details of construction of the particular embodiment thereof illustrated by the drawing or hereinbefore described.

I claim:

1. In combination with a desk top and a swingable lid therefor having in its under side a transversely-extending groove with overhanging sides, means for mounting the lid on the desk top comprising: a hinge having a leaf secured to the desk top and an elongated leaf seated in the groove in con- 100

tact with its sides and having an outer end portion extending outside the groove and contacting the under surface of the lid; and a filler strip inserted into the groove between 5 and contacting the elongated leaf and the bottom of the groove.

2. In combination with a desk top and a swingable lid therefor having in its under side a transversely-extending groove with 10 inwardly diverging sides, means for mounting the lid on the desk top comprising: a hinge having a leaf secured to the desk top and an elongated leaf seated in the groove having a middle portion and side portions 15 extending inwardly therefrom and parallelly with the sides of the groove; and a separate filler strip inserted into the groove contacting the bottom thereof and having inclined sides parallel with and contacting the side portions of the elongated leaf.

3. In combination with a desk top having a friction plate, and a swingable lid therefor having in its under side a transversely extending groove with overhanging sides, 25 means for mounting the lid on the desk top comprising: a hinge having a leaf secured to the desk top and an elongated leaf seated in the groove in contact with the sides thereof and having an integral plate frictionally bearing on the friction plate of the desk top; and a filler strip inserted into the groove between and contacting the elongated leaf and the bottom of the groove.

4. In a structure of the character described: 35 a broad flat member having a transversely extending groove with inwardly diverging sides; an elongated member seated in the groove having a middle portion and side portions extending inwardly therefrom and parallelly with the sides of the groove; and a separate filler member inserted into the groove, contacting the bottom thereof and having inclined sides parallel with and contacting the side portions of the elongated member.

5. In combination with a desk top and a swingable lid therefor having in its under side a transversely-extending groove with overhanging sides, means for mounting the lid on the desk top comprising: a hinge having a leaf secured to the desk top and an elongated leaf seated in the groove in contact with its sides and having an outer end portion extending outside the groove, contacting the under surface of the lid and secured thereto.

6. In combination with a desk top and a swingable lid therefor having in its under side a transversely extending groove with 60 overhanging sides, means for mounting the lid on the desk top comprising: a hinge having a leaf secured to the desk top and an elongated leaf seated in the groove in contact with its sides and having an outer end portion extending outside the groove and con-

tacting the under surface of the lid; and means for securing said leaf to the lid in longitudinally adjusted position relative thereto.

In testimony whereof I have hereunto set 70 my hand at Grand Rapids, Michigan, this 6th day of August, 1930.

RALPH K. MERRILL.
